THOMAS E. CLARK, OF DETROIT, MICHIGAN.

AUTOMATIC TRAIN-CONTROL APPARATUS.

1,284,239.

Specification of Letters Patent. Patented Nov. 12, 1918.

Original application filed February 26, 1912, Serial No. 679,803. Divided and this application filed June 28, 1913. Serial No. 776,239.

To all whom it may concern:

Be it known that I, THOMAS E. CLARK, a citizen of the United States, and a resident of Detroit, in the county of Wayne and State 5 of Michigan, have invented a new and Improved Automatic Train-Control Apparatus, of which the following is a specification.

This invention relates to automatic train control apparatus designed for use in connection with block signal systems for rail- 10 ways, and especially to that type shown in my prior application Serial Number 679,803, filed Feb. 26, 1912, of which this application is a division, and consists in the mechanism 15 mounted on the tender or locomotive, whereby by the action of train brakes and signals of various types are controlled.

This invention consists in a receiving circuit mounted upon a tender, locomotive or 20 other vehicle adjacent to but separated from a wayside circuit, including a translating mechanism, and means to ground said receiving circuit; and train controlling apparatus governed by said receiving circuit and 25 translating device including a source of electric current, whereby the proper signals will be given when the current in the wayside circuit ceases.

It further consists in forming the receiving 30 circuit of two branches, each having portions adjacent to and parallel to the wayside circuit, but out of alignment with each other.

It further consists of the details illustrated 35 in the accompanying drawing and particularly set forth in the claims.

In the accompanying drawing, Figure 1 is a diagrammatic view of the apparatus carried on the locomotive for controlling the 40 brakes and signals and a circuit for high-potential high-frequency oscillating current in operative association therewith. Fig. 2 is a vertical transverse section of the main relay.

Similar reference characters refer to like parts in both views.

Fig. 1 is a substantial reproduction of Fig. 5 of my former application Serial Number 679,803, and the device for transmitting the 50 high tension high-frequency current to the wayside conductor may be tersely described as follows:—further details of description being found in said former application.

The track equipment of each block A, B and C consists of feed wires 6 and 7, the 55 track-circuit wires 8 and 9 connecting to the ends of rails *a* of the next adjacent block, which wires connect to the track-relay or electro-magnet 10, the primary coil of the transformer 14, the circuit of which includes 60 a reactance regulator 15 and the armature 16 of the electro-magnet 10, the lines 17 and 18 connecting to the armature 16 and the reactance regulator, and the switch 19 connecting this circuit to the lines 6 and 7. 65

The drawing further shows the secondary coil of the transformer 14, the rotary interrupter 29—30 (which is fully explained in my former application Serial Number 702,013, filed June 6, 1912), the electrodes 70 31 so positioned as to leave spark gaps 20 between their inner ends and the rotary interrupter, the condensers 23, the copper inductance or linking coil 24, the adjustable contact line 25 leading to the main limb 27 75 of the wayside circuit and the line 26 leading to the pick-up limb 28 or counterpoise of this circuit, which limbs are out of alignment but parallel with each other and with the track rails *a*. In the present case as in 80 the original application, the track is divided into blocks A, B and C by means of insulators 1, and while the short limb 28 or counterpoise of the wayside circuit of each block terminates at the insulation at the forward 85 end of the block, (as trains run on that track) the main limb 27 extends beyond the insulation at the other end of the block into the next adjacent block.

The receiving circuit and the local operating circuit mounted on the locomotive or tender, are shown in substantially the same manner as in the former application. The receiving circuit is of variable inductance or capacity, and if in proximity to the high-potential high-frequency wayside circuit, and properly tuned with the wayside circuit, there will be impressed upon the receiving circuit a high-frequency high-potential oscillating current. If the receiving circuit is 90 sufficiently near to a wayside conductor of high-frequency high-potential current, this action will be different from the usual Hertzian wave action and the current in the receiving circuit will be of sufficient strength 95 100 to cause a lamp placed in the receiving

circuit to glow brilliantly, or to effect the actuation of instrumentalities, either directly or indirectly, for operating signal and train control devices, or for other purposes, although there is no metallic connection between said circuits. The question of tuning, however, is of material importance, for if the receiving circuit is not properly tuned, only a feeble flow of current will be noted therein.

It should be noted that the track-relay 10 of the block in advance, that is, the block C in the drawing, controls the armature 16 that forms a portion of the circuit 15 which supplies energy to the oscillating circuit of the next block in the rear, that is, the block B in the drawing, said relay acting as a circuit closer and opener according as it is energized and deenergized, an axle 20 138 serving to short circuit the rails of the block C and preventing sufficient current passing over the wires 8 and 9 and the winding of the relay 10 to cause the armature 16 to be attracted. This results in the cessation 25 of energy from the way-side circuit.

The local circuit on the engine or tender may be energized in any desired manner, storage batteries preferred, and the current of said circuit operates the various instrumentalities hereinafter described. The receiving circuit comprises a main branch and a pick-up branch, the former utilizing the energy from the wayside circuit member 27, and the other utilizing energy from the 30 counterpoise 28. The receiving circuit is shown diagrammatically in the drawing associated with the wayside circuit and with a diagrammatically indicated generator of high-potential high-frequency oscillations, 35 and with an oscillating circuit, and said receiving circuit comprises harp members 53 of certain capacity, formed of a plurality of strands of wire connected to one terminal of the line 54 and located so as to parallel 40 the main limb 27 of the wayside circuit at a predetermined distance therefrom. The line 54 leads to a binding post 55, thence to a binding post 56 of the main relay 57, and when the relay is energized, to the stationary contact 98 and movable contact 97 of 45 the armature of the relay. The line 59 connects this contact 97 to the thermo-electric relay 60, and the line 59^a connects this relay to the variable inductance 61 and to the 50 ground 62.

The pick-up branch circuit is also mounted on the locomotive, and comprises smaller harp-like elements 63 adjacent and adapted to receive electrical energy from the counterpoise or balancing capacity 28, and disposed in spaced parallel relation thereto. The receiving elements 63 of the pick-up circuit are connected to line 64 leading to binding post 65, and thence to the 55 binding post 66 on the main relay, thence

by the metallic frame 96 of said relay to the rear contact 58, the movable contact 97, and on line 59 through thermo-electric relay 60, thence to inductance 61, and to earth 62.

Said pick-up branch circuit is closed when the main relay 57 is deenergized, and being thus closed is the first to receive current influence from the wayside circuit, which current influence flowing along the 75 line of the pick-up branch circuit energizes the thermo-electric relay to close a local circuit including the main relay 57 and energizes said main relay 57 to put into operative position the train control and signal 80 apparatus as hereinafter explained.

The local circuit which also includes the thermo-electric relay and main relay or electro-magnet 57, comprises the lines 67 and 67^a, which lead to the bus-bars, of 85 which 68 is the positive and 69 the negative. These bus-bars are employed as a matter of convenience for making electrical connection with the several electrical devices and are in turn connected with the storage 90 battery 70 by means of the lines 71 and 71^a through a suitable switch 72.

The thermo-electric relay is fully described in my former application Serial Number 680,970, filed March 1st, 1912, and 95 is so constructed that so long as a proper high-potential high-frequency current from the wayside circuit is conducted thereto by the line 59 and passes through said relay to the ground, a connection between the lines 100 100 and 67^a of the local circuit will be maintained. It consists of a fine wire filament 78 of high resistance, extending between the ends of the lines 59 and 59^a, and held in tension by the spring 75 and screw 105 76. When this filament becomes heated sufficiently by the current passing over it to sag, the fiber 81 will permit rotation of the disk 86, and connection is effected between the ends of the lines 67 and 67^a. When 110 insufficient current passes over the filament 78, the circuit between the lines 67 and 67^a will be opened because of the turning back of the disk 86 by the fiber 81 under stress of the cooled filament 78.

A frame 92 of the main relay is mounted on a suitable base and carries binding posts 56, 63, 104^a and 134 for the several lines as well as the electro-magnets 57. The armature 94 is pivoted at 95 and carries a 120 plurality of spring contact members 103, 122 and 97, adapted, when the relay is energized, to make contact with the front contacts or binding posts 104, 121 and 98; and when the relay is deenergized and drops 125 back by gravity, contacts 103 and 97 make contact with the rear binding posts 132 and 58 respectively.

When the relay is deenergized, the pick-up branch 64 of the receiving circuit is 130

closed through the post 66 of the main relay to which said line leads, through the metal portion 96 of the frame of the relay with which said binding post is in electrical contact, through the back contact 58, the spring contact member 97 on the armature, and through the line 59 leading from said contact member to and through the thermo-electric relay and the inductance 61 to the ground.

The effect therefore of the initial passage of a current over the pick-up branch of the receiving circuit will be to energize the thermo-electric relay and close the local circuit 67 and 67', thereby causing the energizing of the main relay, causing it to attract its armature and carry the movable contact members thereon into engagement with the front contacts of the relay. This energizing of the main relay produces several results by reason of the closing of the several circuits through the front contacts thereof, the first being that of closing the main receiving circuit through the contacts of said relay as follows: Upon the energization of the main relay and the consequent attraction of its armature, the receiving circuit, including the line 54, will be closed, and will comprise the binding post 56, the front contact 98 of the relay, which will then be engaged by the movable contact 97, (which will at that time be swung out of engagement with the rear contact 58,) and through the line 59 connected with said movable contact to the thermo-electric relay 60, the variable inductance 61, and ground 62. This closing of the main receiving circuit by the energization of the main relay will cause the high-potential current which is being impressed into the harps 53 of said circuit to flow constantly across the fine wire filament 78 of the thermo-electric relay, notwithstanding the fact that the actuation of the armature of the main relay will have opened the pick-up circuit by separating the movable contact 97 from the back contact 58. This current over the filament 78 of the thermo-electric relay will maintain closed the local circuit in which the main relay is located so long as there is a flow of current in the receiving circuit, which is the normal condition when a train is running under conditions of safety.

Upon the actuation of the main relay through the closing of the local circuit, circuits are closed through the solenoids 99 and 100 respectively, the circuit of solenoid 99 being as follows: the path of the current is from the positive bus-bar 68 on line 101 to binding post 102, thence to movable relay contact 103, relay contact 104, line 105, leading from binding post 104 of said front contact and joined line 106 to terminal 107 of the solenoid coil 99, thence from terminal 108 of said coil on line 109 to line 110, and on said line to negative bus-bar 69. This

closing of the circuit of the solenoid 99 will energize it and actuate its core 111 to close the valve 112, the stem 113 of which is connected to the said core, said valve controlling the train pipes 114 of the air brake system.

It is designed to employ in connection with this system an audible alarm in the form of a whistle, illustrated at 115, connected with an air or steam pipe 116, which is controlled by a valve 117. Like valve 112 the stem of valve 117 is connected with solenoid 100 and is actuated by the energization of said solenoid as is valve 112. While the solenoid remains energized the valve 117 is closed and air or steam is cut off from the whistle. Upon the deenergization of the magnet 100 the whistle valve will open and air or steam under pressure from any suitable source is allowed to pass into the whistle and sound an alarm. The circuit of solenoid 100 includes the line 110 which leads from the coil terminal 118 thereof to the negative bus-bar 69. The line 119 which leads from the positive bus-bar 68 to the binding post 120 of the front contact 121 of the main relay, thence, when said relay is energized, through the movable contact 122 and therefrom on line 123 to the other terminal 124 of the winding of the solenoid 100. It will therefore be apparent that the energizing of the main relay closes the circuit of solenoid 100 simultaneously with the closing of the circuit to the solenoid 99, said solenoids being thereby energized to actuate their respective valves to close the train pipe 100 and the air pipe leading to the whistle. Another further function performed by the energization of the main relay is the closing of a circuit through the colored lamp 125, preferably green, which is located in the locomotive cab to serve as a visual signal, and whose circuit comprises the line 119 leading from the positive bus-bar, the contacts 121 and 122, the line 123, the connected line 126 which leads to said lamp, and the return line 127 which connects to the negative bus-bar 69, thus causing a flow of current from the battery 70 through said lamp while the main relay remains energized.

It will now be understood that while the receiving circuit is receiving the energy impressed upon it by the wayside circuit, the main relay will remain energized and keep closed the circuits for the currents that will energize the solenoids to maintain the whistle and train valves closed, and at the same time keep closed the circuit of the signal lamp 125, which will preferably be green in accordance with the system employed in railway signals to indicate a clear track and conditions of safety. This visual signal is not necessary in connection with the audible whistle, but its use is preferred as an additional safeguard. The engine man in the cab, as long as this condition obtains, will

know that the track is clear, and that he may drive his train in accordance with its schedule.

So long as the block ahead is clear, there is nothing to prevent the train under consideration to run as the engine man may see fit. But as soon as the block C ahead is occupied, the track-circuit to the relay 10 of block B becomes short-circuited, thereby cutting off such a large proportion of the current to the relay 10 that the armature 16 will fall away and open the circuit to the transformer 14 of block B, thereby causing a cessation of the supply of energy to the wayside circuit of block B, comprising the limbs 27 and 28 of that block. A train entering block B will soon be stopped, for the main limb 27 of the wayside circuit will be deprived of its energy and will fail to impress proper current flow in the receiving circuit of the train. This condition will allow the main relay of that train in block B to open and thus open the circuits to the solenoids 99 and 100, resulting in the valves 112 and 117 controlled thereby to open, and the brakes being applied.

In view of the possibility of the whistle 115 not sounding through the failure of the air or for some other cause, there is provided a visual signal in the form of a red light 129 which is located in a circuit comprising the line 101 leading from positive bus-bar 68, movable contact 103 of the main relay, and back contact 132, on metallic frame 133, binding terminal 134 connected therewith, on line 135, and on connected line 136 leading to said lamp. The return side of said circuit is completed by short line 137 connected to line 127 which leads to the negative bus-bar 69, whereby, by opening of the main relay, current will be caused to flow through the circuit of the red lamp 129 and by the illumination thereof afford an additional visual danger signal.

Should the engine man desire to release the brakes of his train and proceed slowly forward under check until the end of the block is reached, he may do so by depressing the release key 139 which will close the circuit across the terminals of the lines 127 and 140, said line 127 leading to the negative bus-bar 69 and the circuit being completed on line 101 from the positive bus-bar, the rear contact 132, the frame 133, the binding post 134, the line 135 to line 141, to one terminal of the winding of the relay 142, and from the other terminal of said winding on line 143 to line 140 back to said release key 139, thus causing a flow of current from the battery 70 through the relay 142, energizing said relay and actuating its armature 144 to press the movable contact 145 against the contact 146. This effects the closing of the local circuit through the relay 142 comprising the short line 147 from said contact 146,

the connected line 127, negative bus-bar 69, through the battery, then over positive bus-bar and line 101 leading therefrom, movable contact 103 of the main relay, rear contact 132, metal frame 133, and lines 135 and 141, to one terminal of the winding of said relay, and from the other terminal of said winding on line 143 to movable contact 145.

It will thus be seen that the momentary closing of the release key (which is self-restoring) will establish a local circuit through the relay 142 and maintain said relay closed notwithstanding the circuit of the release key may be immediately opened by releasing said key. The movement of the armature 75 of the relay 142 not only closes its local circuit just described, but also actuates the movable contact 148 and carries it into engagement with the contact 149, thereby closing a circuit at said contacts, comprising the line 150 leading to the positive bus-bar, then to the storage battery and back to the negative bus-bar and over the lines 110 and 109 to one terminal of the winding of the solenoid 99 and from the other terminal of said winding on line 106 to line 151 and to the other movable contact 148, thus causing a flow of current through solenoid 99 and energizing said coil to lift its core and close valve 113 of the train pipe 114, thereby releasing the brakes and enabling the engine man to proceed under control, as shown in Fig. 1. But the whistle 115 will continue to blow and the red light will still glow as a constant warning of danger.

As soon as the block C ahead becomes clear, the track relay 10 of the block B will again be energized, thereby closing the generator circuit for block B, restoring energy to the main wayside circuit 27 of said block and enabling the train lying in block B to pick up energy from the wayside circuit conductor 27. This will result in the closing of the main relay 57 through the action of the thermo-electric relay 60, in the energizing of the solenoids 99 and 100 and the closing of the train valve 112 and whistle valve 117, the extinguishing of the red lamp and the ignition of the green lamp.

The closing of the main relay 57 will also break the local circuit of the relay 142 and open the circuits at the contacts 145 and 146, and 148 and 149 respectively. This restoration of the apparatus in the engine cab by the closing of the main relay through the operation of the thermo-electric relay in the receiving circuit will indicate a condition of safety under which the engine man may proceed.

As was stated, the relay 142 was energized 125 by a current which passed from the positive bus-bar 68 over the wire 101 to the movable contact 103, frame 133, binding post 134, wire 135 to the relay, and from the relay over the wire 143, contacts 145 and 146, wires 130

147 and 127 to the negative bus-bar 69. When the main relay 57 is energized, the movable contact will be disengaged from the contact 132 carried by the frame 133, and this local circuit to the relay 142 will be opened, resulting in a separation of the contacts 145 and 146, and of the contacts 148 and 149.

Referring again to the arrangement of the insulated blocks or sections of the track and the location of the main wayside circuit and the counterpoise with respect to the track, it will be noted that the member 27 of block C extends beyond the point of insulation of the rails into block B, and that the counterpoise 28 of block B extends from the end of the main limb 27 of block C to the insulation between blocks B and C. A train stopping in the block next beyond C, which may be termed D, will short circuit the track circuit for said block and cut off the current supply from the main limb 27 of the wayside circuit of the block C. A following train will have clear indication until it reaches the end of block B, that is, until it reaches the end of the member 27 of block C.

When that point is reached, and the train stops there, the harp 63 of the pick-up branch of the receiving circuit will extend over the counterpoise 28 of block B, and the engine man will receive an intermittent indication of safety until the train that is in block D shall have passed into the next block ahead. The reason that the indications are intermittent is, that, while the counterpoise 28 of block B will be energized, the main wayside circuit 27 of block C, which extends into block B, will be without current because of the presence of a train in block D.

The current passing through the thermoelectric relay from the pick-up branch of the receiving circuit will actuate it to close the local circuit of the main relay and energize said relay to attract its armature and break the pick-up branch of the receiving circuit, but said main relay will not remain energized because the main wayside circuit for block C is without current, permitting the armature of said relay to drop back and again close the pick-up branch of the receiving circuit, when the main relay will again become momentarily energized and the pick-up branch of the receiving circuit will be again broken, thus causing a vibration of the armature of the main relay and an intermittent opening and closing of the circuits controlling the signal and train stopping devices; therefore, the engine man will be obliged to hold his train at the entrance of block C until the train ahead has given to block C a clearing indication by passing from block D. The passing of the train from block D will restore the track

circuit in said block, and reenergize the track relay, thereby closing the generating circuit for block C, and supplying a high-frequency, high-potential current to the wayside circuit 27 and 28 of said block. The return of current to the wayside circuit of block C will be manifest to the engine man, whose train is lying at the entrance of said block by a continued energization of the main relay and the consequent closing of the train line and whistle valves, as well as by the extinction of the red light and the illumination of the green light.

The performance of the functions just described indicates a condition of safety, under which the train held at the entrance of block C may proceed under usual running conditions with the assurance that the train in front is at least two full blocks ahead.

By extending the harps of the receiving circuit and the pick-up branch thereof in opposite directions as shown, provision is made for rendering them operative whether the train be running forward or backward.

It will now be understood that the generation of a high-frequency, high-potential energy for the wayside circuit is controlled by a track circuit in such a manner as to afford a continuous supply of energy to the wayside circuit under conditions of safety, and to cause a suspension of said energy in said circuit under conditions of danger within or in respect to the zone guarded or controlled by said apparatus.

It is believed that one portion of the fixed conductor parallel with the track together with the harp of the receiving circuit on the vehicle constitute the metallic elements of a condenser, and that another portion of said fixed conductor together with the track rail form the metallic elements of a second condenser, the intervening air in the case of both condensers serving as a dielectric. With these elements so acting a circuit is formed through a part of the fixed conductor to the receiving circuit on the vehicle, thence through the responder to the ground, and back to the other part of the fixed conductor by way of the ground and the track rail. This accounts for the strong current through the responder and for other effects observed in practising this invention.

I claim—

1. In a railway system of train control adapted for use with a wayside conductor comprising two limbs out of alignment with each other and adapted to transmit high-frequency, high-potential current, a vehicle, a plurality of receiving conductors mounted respectively adjacent each of the limbs of the wayside conductor, a translating device, a relay having a plurality of pairs of contacts respectively adapted to alternately close the circuits between the translating de-

vice and the receiving conductors, a current source and brake mechanism on the vehicle, and circuits between said relay, the translating device and the current source whereby said brake mechanism will be controlled by said translating device.

2. In a railway system of train control adapted for use with a wayside circuit, each comprising a long and a short limb out of alignment with each other and adapted to transmit high-frequency high-potential current, a vehicle, a main receiving conductor on the vehicle adjacent the longer limb of the wayside circuit and a pick-up conductor 10 mounted on the vehicle adjacent the shorter limb of the wayside circuit, a translating device, a main relay, a current source and a brake mechanism all mounted on the vehicle, circuits between the main and pickup conductors and the main relay, a single circuit between the relay and the translating device, which circuit is connected to the pick-up circuit when the relay is deenergized and to the main receiving circuit when the relay 25 is energized, and an independent circuit between the current source, the relay and the translating device which is operative when current is received by the pick-up circuit.

3. In a railway system of train control adapted for use with a wayside circuit, each comprising a long and a short limb out of alignment with each other and adapted to transmit high-frequency high-potential current, a vehicle, a main receiving conductor 30 on the vehicle adjacent the longer limb of the wayside circuit and a pick-up conductor mounted on the vehicle adjacent the shorter limb of the wayside circuit, a translating device, a main relay, a current source and a brake mechanism all mounted on the vehicle, circuits between the main and pick-up conductors and the main relay, a single circuit between the relay and the translating device, which circuit is connected to the pick-up 35 circuit when the relay is deenergized and to the main receiving circuit when the relay is energized, and an independent circuit between the current source, the relay and the translating device which is operative when current is received by the pick-up circuit, an electric control for the brake-mechanism, and electric circuits between the current source, the main relay and said electric control, whereby the brake mechanism is held 40 inoperative when the relay is energized.

4. In a railway system of train control adapted for use with a wayside circuit, each comprising a long and a short limb out of alignment with each other and adapted to transmit high-frequency, high-potential current, a vehicle and the following mechanism 45 mounted thereon, viz:—a main relay provided with two series of contact points and a movable member adapted to close the circuits of the points of each series when the

relay is energized or deenergized respectively, a thermo-electric relay connected to the main relay, a main pick-up conductor mounted adjacent the main limb of the wayside circuit and connected to the main relay 70 and in circuit with the thermo-electric relay when the main relay is energized, a pick-up conductor connected to the main relay and in circuit with the thermo-electric relay when the main relay is deenergized, a current 75 source, circuits between the current source, the main relay and the thermo-electric relay over which current will flow to energize the main relay whenever current passes from the wayside circuit to either of the receiving 80 conductors on the vehicle, a brake mechanism for the vehicles, electric means for holding it inoperative, and electric circuits connecting to said current source, main relay and brake controlling means over which current passes when the main relay is energized, to hold the brake mechanism inoperative. 85

5. In a railway system of train control, the combination with a railway vehicle, of a main receiving conductor and a pick-up conductor mounted thereon adjacent two limbs of a wayside circuit which are out of alignment with each other, a main relay mounted on the vehicle, a thermo-electric 90 relay, a current source, and electric devices for controlling the operation of the vehicle, and electric circuits between the receiving conductors and the main relay, between the main relay and the thermo-electric relay, 95 between the main relay and the electric devices for controlling the operation of the vehicle, and between the current source and the main relay, whereby current may flow from the pick-up conductor to the thermo-electric relay when the main relay is deenergized, from the main receiving conductor to the thermo-electric relay when the main relay is energized, from the current 100 source to energize the main relay when current passes to the thermo-electric relay, and from the current source to the electric devices for controlling the operation of the vehicle when the main relay is energized. 105

6. In a railway system of train control, the combination with a railway vehicle, of a main receiving conductor and a pick-up conductor mounted thereon adjacent two limbs of a wayside circuit which are out of alignment with each other, a main relay 110 mounted on the vehicle, a thermo-electric relay, a current source, and electric devices for controlling the operation of the vehicle, and electric circuits between the receiving conductors and the main relay, between the main relay and the thermo-electric relay, between the main relay and the electric devices for controlling the operation of the vehicle, and between the current source and the main relay, whereby current may flow from the 115

- pick-up conductor to the thermo-electric relay when the main relay is deenergized, from the main receiving conductor to the thermo-electric relay when the main relay is energized, from the current source to energize the main relay when current passes to the thermo-electric relay, and from the current source to the electric devices for controlling the operation of the vehicle
- 5 when the main relay is energized, an audible signal, electric means for holding the same inoperative, and circuits between said electric means, the current source and the main relay which circuits are closed when the main relay is energized and open when the main relay is deenergized.
- 10 7. In a railway system of train control, the combination with a railway vehicle, of a main receiving conductor and a pick-up conductor mounted thereon adjacent two limbs of a wayside circuit which are out of alignment with each other, a main relay mounted on the vehicle, a thermo-electric relay, a current source, and electric devices for controlling the operation of the vehicle, and electric circuits between the receiving conductors and the main relay, between the main relay and the thermo-electric relay, between the main relay and the electric devices for controlling the operation of the vehicle, and between the current source and the main relay, whereby current may flow from the pick-up conductor to the thermo-electric relay when the main relay is deenergized, from the main receiving conductor to the thermo-electric relay when the main relay is energized, from the current source to energize the main relay when current passes to the thermo-electric relay, and from the current source to the electric devices
